Primary Examiner — Karen S Acker*Assistant Examiner* — Jasmine Mlinarcik(74) *Attorney, Agent, or Firm* — George C. Rondeau, Jr.;
Davis Wright Tremaine LLP**(57) CLAIM**

The ornamental design for a wide brim hat, as shown and described.

DESCRIPTIONFIG. 1 is a top front perspective view of a wide brim hat.
FIG. 2 is a right side elevational view thereof.

FIG. 3 is a front elevational view thereof.

FIG. 4 is a left side elevational view thereof.

FIG. 5 is a rear elevational view thereof.

FIG. 6 is a top plan view thereof; and,

FIG. 7 is a bottom plan view thereof.

The broken lines depict portions of the wide brim hat that form no part of the claim. The square-pattern applied along the crown of the wide brim hat is netting.
